Primary Examiner — Jennifer L Watkins*Assistant Examiner* — Christine Tucci(74) Attorney, Agent, or Firm — Lerner David LLP(57) CLAIM

The ornamental design for a footwear, as shown and described.

DESCRIPTION

FIG. 1 is a front right perspective view of a footwear showing our new design;

FIG. 2 is a right side elevational view thereof;

FIG. 3 is a rear elevational view thereof;

FIG. 4 is a top plan view thereof;

FIG. 5 is a bottom plan view thereof; and,

FIG. 6 is an enlarged portion of FIG. 2.

The broken lines of even length depict portions of the footwear that form no part of the claimed design. The broken lines of uneven length are boundary lines that form no part of the claimed design. The broken lines of even length in FIG. 2 that encircle portions of the footwear form no part of the claimed design.
